UNITED STATES PATENT OFFICE.

JOHN F. O'CONNOR, OF CHICAGO, ILLINOIS, ASSIGNEE TO WILLIAM H. MINER, OF CHICAGO, ILLINOIS.

RAILWAY DRAFT-RIGGING.

1,186,038.

Specification of Letters Patent.

Patented Apr. 20, 1915.

Application filed March 9, 1914. Serial No. 823,276.

To all whom it may concern:

Be it known that I, JOHN F. O'CONNOR, a citizen of the United States, residing at Chicago, in the county of Cook and State of Illinois, have invented a certain new and useful Improvement in Railway Draft-Rigging, of which the following is a full, clear, concise, and exact description, reference being had to the accompanying drawings, forming a part of this specification.

My invention relates to improvements in draft rigging for railway cars.

The object of my invention is to provide a draft rigging for railway cars of efficient operation.

In the drawings forming a part of this specification, Figure 1 is a side elevation, partly in vertical longitudinal section, of a draft rigging embodying my invention; Fig. 2 is a plan view, partly in horizontal section, on line 2—2 of Fig. 1; Fig. 3 is a cross-section taken on line 3—3 of Fig. 1.

Referring to the drawings, the numerals 4—4 indicate draft sills or parts of the car frame to which the draft rigging is applied; 5—5 side plates or stop-members secured to the sills and having front stop-shoulders 6—6, rear stop-shoulders 7—7, front limiting stop-shoulders 8—8, and rear limiting stop-shoulders 9—9.

The numeral 10 designates a draw-bar, only the rear end thereof being shown in the drawings, and having a draft-yoke 11 keyed thereto by the key 12 passing through the head 13 of the yoke and through the draw-bar, the key being extended at its ends through the elongated longitudinal slots 14—14 in the adjacent portions of the side plates and draft sills. The tie plate 15, secured to the draft sills preferably by the bolts 16—16, is adapted to support the draft gear 17 within the draft yoke. The draft gear 17 is adapted to be engaged at its respective front and rear ends by the front follower 18 and the rear follower 19. The draft gear comprises a shell 20 having friction elements 21 and spring elements 22 mounted therein. The friction elements comprise the wedge 23 adapted to spread the friction shoes 24—24, and having anti-friction rollers 25 mounted between the wedging faces of the wedge and the adjacent wedging face of each friction shoe. The friction shoes are preferably three in number, and in annular arrangement within the

shell, the shell being preferably cylindrical in shape, having the hollow forwardly opening chamber 26 therein. The spring elements within the shell preferably comprise an outer spring 27 and an inner spring 28 nested therein. A clip or spring seat 29 having a rearwardly opening recess 30 therein is mounted between the friction elements and the springs 27 and 28. The said spring seat engages the inwardly projecting shoulders 31 with which the friction shoes are provided, and has an outwardly extended flange 32 which engages against the rear ends 33 of the friction shoes. The outer spring 27 is forwardly seated against the flanges 32 of the said spring seat 29, and is rearwardly seated against the shell 20. A connecting rod 34 passes through the wedge 23, the spring seat 29 and through the rear end of the shell where it is provided with a nut 35 which is received within the recess 36 in the rear end of the shell. At its forward end the connecting rod 34 is provided with a nut 37 which is received within the forwardly opening recess 38 in the wedge. Intermediate its ends the connecting rod 34 is provided with a preferably integral shoulder or seat 39, the inner spring 28 being seated between said shoulder and the rear end of the shell, and a further spring 40 being seated between the said seat or shoulder 39 and the spring seat 29, the greater portion thereof in preferable arrangement of the parts being mounted within the recess 30 in the spring seat or clip 29.

In the assembling of the parts of the draft gear, the spring 40 is preferably placed under an initial compression, thus exerting a pressure against the shoulder 39 of the connecting rod and holding the spring seat 29 in engagement against the friction shoes. The pressure of the spring 40 against the shoulder 39 of the connecting rod exerts a rearward pull upon the wedge 23, thus holding the parts of the friction mechanism within the shell in close relation so that upon initial movement of the friction mechanism the parts thereof will operate immediately in affording frictional resistance to the draw-bar's movements. In this arrangement, it will be observed that while the springs 27 and 28 may be placed under an initial compression when the parts of the draft gear are assembled, it is not necessary so to do in order to hold all the parts of

the draft gear in closely assembled relation or to take up the wear of the parts thereof. These functions will be performed by the spring 40 in connection with the seating 5 thereof upon the connecting rod itself, and the springs 27 and 28 may be mounted within the shell without placing any initial compression thereon. By the use of the spring 40 in the relation with the other parts shown 10 and described herein, springs of great stiffness and high capacity may be used without placing the springs under an initial compression, thereby enabling the heavy high 15 capacitated springs to be used for affording an easier initial movement, and thereby insuring an easier starting of trains than would be assured or afforded were very stiff springs used and placed under initial compression for the purpose of holding the parts 20 within the shell in closely assembled relation.

I claim:

1. In a draft gear for railway cars, the combination with a shell, of friction shoes, 25 a wedge and springs within the shell, a connecting rod engaging the shell at one end and the wedge at the other end, the connecting rod being provided intermediate its

ends with a shoulder, and one of the springs being seated between said shoulder and the 30 friction shoes.

2. In a draft gear for railway cars, the combination with a friction shell, of friction shoes and a wedge within the shell, a spring seated between the shell and friction 35 shoes, a connecting rod engaging the wedge at one end, and the shell at the other end, a shoulder upon said connecting rod, a spring seated between said shoulder and the shell, and a further spring seated between 40 said shoulder and the friction shoes.

3. In a draft gear for railway cars, the combination with a friction shell, friction shoes and a wedge within the shell, of a connecting rod engaging the shell at one end 45 and the wedge at the other end, said connecting rod being provided with a seat intermediate its ends and rigid thereon, and a spring interposed between said seat and the friction shoes and held under initial compression. 50

JOHN F. O'CONNOR.
